UNITED STATES PATENT OFFICE.

GRAHAM H. PIGGOT, OF CHICAGO, ILLINOIS, ASSIGNOR TO FEDERAL STEEL FIXTURE COMPANY, OF CHICAGO, ILLINOIS, A CORPORATION OF ILLINOIS.

LOCKER SYSTEM.

1,245,022.

Specification of Letters Patent. Patented Oct. 30, 1917.

Application filed August 30, 1916. Serial No. 117,613.

To all whom it may concern:

Be it known that I, GRAHAM H. PIGGOT, a citizen of the United States of America, and resident of Chicago, Cook county, Illinois, have invented a certain new and useful Improvement in Locker Systems, of which the following is a specification.

My invention relates to locker systems for gymnasiums, golf clubs, and other places where private lockers are necessary and desirable.

The object of my invention is to provide an improved construction and arrangement of such character that the lockers or drawers in which the clothing is kept will be of less size than heretofore, whereby the system will be less expensive and occupy less space, and in which the private drawers or lockers are supplemented by a certain number of compartments which are common to the members of the club or users of the system, thereby to enable each member or user to have what is practically a full locker service, including the locking up of both the street clothing and the gymnasium or other suits at the proper times, but in a system in which each private locker or drawer is too small to hold the street clothing, as will hereinafter more fully appear.

It is also an object to provide certain details and features of construction and combinations tending to increase the general efficiency and desirability of a condensed locker system of this particular character.

To these and other useful ends, my invention consists in matters hereinafter set forth and claimed.

In the accompanying drawings:—

Figure 1 is a front elevation of a section of steel shelving containing the lockers or drawers of a locker system embodying the principles of my invention.

Fig. 2 is a horizontal section on line 2—2 in Fig. 1.

Fig. 3 is a vertical section on line 3—3 in Fig. 1.

Fig. 4 is a front elevation of the steel dressing cabinets or compartments which supplement the lockers shown in Figs. 1, 50 2 and 3 to make up the complete system.

Fig. 5 is a vertical section on line 5—5 in Fig. 4.

Fig. 6 is a fragmentary perspective view of a portion of the construction shown in Figs. 4 and 5.

Fig. 7 is a horizontal section on line 7—7 in Fig. 5.

Fig. 8 is a vertical section on line 8—8 in Fig. 5.

As thus illustrated, my invention comprises a structure A of steel or other suitable material, having openings a arranged one above the other, in vertical columns, for the lockers or removable drawers B, which latter may be of any suitable construction. 60 As shown, these lockers or drawers are provided at their front ends with locks b for engaging the lower edges of the openings a to hold the lockers or drawers against removal. At its rear end, each locker or drawer B is provided with an opening or hand-hole C through which an attendant can obtain access to remove clothing or articles of wearing apparel, or for any other purpose. Preferably, therefore, the structure A has 70 a passageway D in rear thereof, which is provided with a door d for gaining access thereto. The attendant, by entering this passageway D, can gain access to any of the drawers or lockers through the openings C; 80 in the manner explained. The door d can be provided with a suitable lock E to prevent improper access to the passageway back of the drawers. These drawers or lockers B are made just large enough to contain the 85 gymnasium suit, or the golf suit, or other similar wearing apparel, but are not large enough to contain the ordinary street shoes and clothing, etc., whereby the entire structure is very much condensed and will not 90 occupy as much space as would be the case if these drawers were to be used to contain the street clothing while the user is on the floor of the gymnasium or on the golf course.

Figs. 4 to 8 show the construction of the 95 dressing cabinet or auxiliary compartment to be used in common by those who occupy the drawers or lockers previously described. Of course, with a large number of drawers or lockers, there will then be a suitable num- 100

ber of the cabinets shown in Figs. 4 to 8, but there need not be a large number of these cabinets than the number of people who can occupy the gymnasium floor at the 5 same time, or who can use the golf course at the same time. In other words, in a gymnasium or club having a thousand members, there would be a thousand drawers or lockers B, of the kind shown and described, but 10 the number of dressing cabinets F, such as shown in Figs. 4 to 8, inclusive, would be very much less, and would only be a percentage of the said total number of drawers or lockers, depending upon how many people 15 could occupy the floor of the gymnasium at the same time, or could properly be on the golf course at the same time. In fact, the number of dressing cabinets F might be even less, as in some instances it would be 20 found that the maximum number of people occupying the gymnasium floor, or using the golf course, would never be as large as the full capacity thereof. These cabinets F are preferably constructed of steel and 25 sheet-metal, or other suitable material, and are rectangular and upright in form, being provided with legs f to support them a distance above the floor. Each cabinet is, therefore, provided with a top wall 1, a rear or 30 back wall 2, side walls 3, and a front door 4, which latter is hinged at 5 to one corner portion of the cabinet. It will be observed that this door is of a height to extend from the top of the cabinet to a point some distance 35 above the bottom 6 of the structure, thus leaving an opening between said bottom and the lower edge of said door. As shown, said door is provided with upper and lower locking bolts 7 and 8, operated by a 40 suitable locking mechanism 9, said upper bolt engaging a cleat 10 on the cabinet to hold the top of the door closed. The bolt 8 has its lower end provided with an out-turned portion 11 which projects under the 45 lower edge of the door. The interior of the compartment may be provided with hooks or hangers for supporting the street clothing of the user, and is preferably just large enough for this purpose.

50 The method of use is as follows: When the gymnasium or golf-club member, or other person, desires to use the locker system, the drawer B is withdrawn from the shelving or rack A, and is carried to the 55 place where the user will then substitute the gymnasium or golf clothes contained in the drawer for the street clothing and wearing apparel. The said street clothing, etc., is then hung up or placed in the cabinet F, 60 and the drawer B is then inserted under the door 4, in the manner shown in Figs. 4, 5, 6 and 7, after the said door is closed. When the drawer B is inserted in place, a cleat 12 at the front end of the drawer engages the

top of the lower end-portion 11 of the bolt 8, thus preventing the bolts 7 and 8 from being returned to unlocking position while the drawer is in place. The lock b of the drawer is then operated to cause its bolt to engage the forward edge-portion of the bottom 6, thus locking the drawer in place and at the same time preventing the door 4 from being opened. To prevent the rear end of the drawer from being tilted upward, should some one improperly attempt 75 to force an entrance by forcing the door 4 outward, a cleat 13 is provided at the back of the cabinet, inside thereof, to extend over the rear end of the drawer, as shown in Fig. 5. The cabinet F thus closed and locked 80 against further entrance thereto by the insertion and locking in place of the drawer B, is now inaccessible by other persons, and cannot be opened until the user returns. The drawer B is then unlocked and removed, the street clothing, etc., is removed from the cabinet, and the golf or gymnasium suit, or other wearing apparel, is then returned to the drawer B, after which the latter is then returned to the rack or locker-structure A, where it is again locked in 90 place. This releases the cabinet F for use by other persons, and in this way the said cabinet is not individual for any particular user of the locker system, but to the contrary is common to all of the members of the gymnasium or club. Thus, a considerable saving is accomplished, as the entire locker system is much less expensive and occupies less space than would be the case 100 if the drawers or lockers B were made large enough to contain the street clothing and other wearing apparel while the gymnasium or other similar suit is in use.

By the construction and combinations 105 shown and described, a self-service locker system is provided, and by this is meant that the user of the system can come and go and make the desired changes in clothing without the assistance of the care-taker or attendant. At the same time, however, the care-taker or other attendant can have access to the rear end of each drawer or locker, so that soiled linen or other things 110 may be removed from the drawers or lockers, and so that the clean laundry can then be distributed among the different drawers or lockers without unlocking and removing them from their respective or allotted compartments. For this purpose, steel or other 115 kind of metal shelving A can be placed a proper distance from the wall of the building, and the passageway thus provided for the structure can then be equipped with a door of any character, such as the door d previously described, or with any other suitable means for preventing access to the passageway. Of course, the openings in the 120 125

ends of the drawers or lockers need not necessarily be large enough to permit the hand to be inserted into the drawer or locker, but to the contrary can be just large enough 5 to permit the care-taker to slide the package of laundry through the opening and into the door. This, however, will depend upon the requirements or practice in different cases, and if desired the said openings 10 may be large enough to permit the care-taker to insert the hand into the drawer. However this may be, the drawers are preferably of such shape and construction that they can be inserted in the lower end of 15 the interior of the dressing cabinet, in the manner explained, in order to keep the cabinet closed and locked until the user returns. During this time, of course, the drawer will indicate who is using the cabinet, assuming 20 that the different drawers are numbered or lettered or marked in some other suitable manner.

When one drawer or locker is transferred to the cabinet F, the rear opening C of such 25 drawer or locker is closed by the rear wall 2 of the cabinet, so that access cannot be had to the drawer or locker when the latter is locked in the cabinet.

I do not limit myself to the exact construction shown and described.

What I claim as my invention is:—

1. In a locker system, a structure divided into compartments, individual storage drawers or lockers for insertion in said compartments, devices to lock the drawers or lockers in place, a dressing cabinet common to the users of said individual drawers or lockers, said cabinet having a space in which any one of said drawers or lockers may be 35 temporarily inserted, so that said users can take turns in occupying said cabinet, and said cabinet having means whereby the locking device of the drawer or locker inserted therein is operative to lock the cabinet in 40 closed condition.

2. In a locker system, a structure divided into compartments, individual drawers or lockers for insertion in said compartments, devices to lock the drawers or lockers in 50 place, a dressing cabinet common to the users of said individual drawers or lockers, said cabinet having a space in which any one of said drawers or lockers may be inserted, and said cabinet having means 55 whereby the locking device of the drawer or locker inserted therein is operative to lock the cabinet in closed condition, said means comprising a door hinged to the cabinet and disposed above the drawer or locker, and locking devices on said door to engage the upper portion of the cabinet and the front portion of the drawer or locker.

3. In a locker system, a structure divided into compartments, individual drawers or

lockers for insertion in said compartments, 65 devices to lock the drawers or lockers in place, a dressing cabinet common to the users of said individual drawers or lockers, said cabinet having a space in which any one of said drawers or lockers may be inserted, said cabinet having means whereby the locking device of the drawer or locker inserted therein is operative to lock the cabinet in closed condition, said cabinet having a bottom wall to support said drawer 70 therein, and said means including a door movably mounted on the cabinet and disposed above the front portion of the drawer or locker when the latter is inserted in the bottom portion of the cabinet.

4. In a locker system, a structure divided into compartments, individual drawers or lockers for insertion in said compartments, devices to lock the drawers or lockers in place, said drawers or lockers having their 80 rear ends provided with openings through which the hand can be inserted, and said structure having a passageway in rear thereof to afford access to said openings, means to prevent access to said passageway, and a 85 cabinet to receive said drawers or lockers and having means to close said openings to prevent access to the drawers or lockers when transferred to said cabinet.

5. In a locker system, a structure providing a plurality of compartments arranged in vertical columns, drawers or lockers for said compartments, and devices to lock the front ends of said drawers or lockers in place, each drawer or locker having its rear 100 end provided with an opening affording access to permit the removal of articles from the drawers or lockers or to permit articles to be placed in the drawers or lockers without unlocking and removing them from the 105 compartments, by the attendant only, said structure having a passageway in rear of said drawers or lockers, and a door to prevent access to said passageway, and a cabinet adapted to receive said drawers or lockers one at a time, so that said cabinet is common to the users of all of said drawers or lockers, and means on said cabinet to close the opening at the rear end of each 110 drawer or locker.

6. The combination of a plurality of storage drawers or lockers, a structure to hold said drawers or lockers in storage position, and a cabinet to temporarily receive only one drawer or locker at a time, so that the persons to whom said drawers or lockers are allotted are compelled to take turns in using said cabinet, and means to lock any occupying drawer in place and the cabinet closed after the transfer of the drawer from 120 said structure to said cabinet.

7. The combination of a plurality of drawers each having a rear opening, a main

structure to hold said drawers and having
means to afford access to said opening of
each drawer, by an attendant, and an aux-
iliary structure to receive said drawers one
5 at a time and having means to close said
opening, so that a drawer is not accessible

through its opening when temporarily re-
tained in said auxiliary structure.

Signed by me at Chicago, Illinois, this
15th day of June, 1916.

GRAHAM H. PIGGOT.
